UNITED STATES PATENT OFFICE.

ELLSWORTH A. HAWTHORNE, OF BRIDGEPORT, CONNECTICUT.

ILLUMINATING APPARATUS.

1,381,637.

Specification of Letters Patent. Patented June 14, 1921.

Application filed October 23, 1917. Serial No. 198,044.

To all whom it may concern:

Be it known that I, ELLSWORTH A. HAWTHORNE, a citizen of the United States, and a resident of Bridgeport, county of Fairfield, and State of Connecticut, have invented an Improvement in Illuminating Apparatus, of which the following description, in connection with the accompanying drawings, is a specification, like characters 10 on the drawings representing like parts.

This invention relates to illuminating apparatus of the type particularly intended for use as a headlight or searchlight for vehicles, and is more especially concerned with means 15 for controlling the concentration and dispersion of the light rays, and for insuring proper illumination of the foreground and distant roadway, while restricting the rays in such a manner as to prevent objectionable 20 glare above a predetermined height from the roadway.

My invention will be best understood by reference to the following description, when taken in connection with the accompanying 25 drawings of certain specific embodiments thereof, while its scope will be more particularly pointed out in the appended claims.

In the drawings:

Figure 1 is a central, vertical, longitudinal 30 section of a headlight embodying my invention;

Fig. 2 is a front elevation of the same;

Fig. 3 is a front elevation of a motor vehicle equipped with a pair of headlights embodying my invention, and illustrating the 35 action of the light rays;

Fig. 4 is a sectional view on line 4—4 of Fig. 3, also illustrating the action of the light rays;

Fig. 5 is a detail plan on an enlarged 40 scale of the light-intercepting means and its mounting;

Fig. 6 is a sectional view on line 6—6 of Fig. 5;

Fig. 7 is a front elevation of a modified 45 form of the light-intercepting means; and

Fig. 8 is a sectional view on line 8—8 of Fig. 7.

Fig. 9 is a view similar to Fig. 1 showing 50 the light intercepting means as applied to a reflector of form different from that shown in Fig. 1.

Referring to the drawings,—first to the 55 form of my invention illustrated in Figs. 1 to 6, inclusive, and more particularly to Figs. 1 and 2,—I have there shown a headlight

comprising a suitable casing 10, within which is mounted an appropriate light-concentrating reflector 11, which may be and is herein of the parabolic type. A suitable 60 light source, preferably an electric bulb 12, provided with filament 13, is associated with, and preferably coaxially disposed with relation to, the reflector, as best shown in Fig. 1. The reflector is open at the front for the passage of the reflected and unreflected rays, while the front of the casing is provided with a suitable light-transmitting element or glazing 14.

In most communities, there are now in 70 force laws regulating the use of headlights for motor vehicles, the idea being to compel the use of headlights which, while furnishing ample illumination of the roadway, shall produce no objectionable glare above a certain height from the roadway. Many attempts have been made to provide suitable 75 devices to comply with the various regulations, but heretofore much difficulty has been experienced in producing a practicable and 80 serviceable device which will eliminate the objectionable glare, without more or less serious reduction of the necessary illumination for the safety of the operators of vehicles, as well as pedestrians, on the roadway. Some 85 devices, while possibly achieving fairly satisfactory results in this direction, are either complex, as well as expensive, or so fragile and delicate as to be injured easily by the shocks and vibrations to which they are 90 subjected.

In producing my invention, I have provided a device which is found in practice to give excellent results as regards illumination of the foreground and distant roadway, 95 while still possessing the necessary simplicity and strength to enable it to withstand the shocks and vibrations to which it is subjected when in use on a motor vehicle.

To this end, I have provided light-intercepting and reflecting means which I will now describe. A light-intercepting element 15 has a segmental wall 16, which for the most part is disposed above the axis AA of the light source and reflector, although in the present example, it is provided with two downwardly and forwardly inclined lateral portions 17, which extend below the axis. This segmental wall may be, and in the present example is, a segment of a cylinder 105 whose axis is coincident with the axis AA of the bulb and reflector. The light-intercept-

ing element 15 also has another wall 18, which in the present example is disk-like and preferably in the form of a segment of a disk, as best shown in Fig. 2, wherein it will 5 be observed that the chord of the segment is formed by a horizontal edge 19 below the axis AA. It should be observed that this edge is below the lowermost part of the filament 13, so that the latter is completely hidden from the eye of a person standing on the 10 roadway when the lamp is so placed that a plane BB containing the edge and the lowermost portion of the filament lies below the observer's eye. Thus, it will be apparent 15 that no direct rays from the light source can reach and blind the eye of the observer.

In the case of a shallow reflector, or one of moderate depth such as represented at 11' in Fig. 9, it is safe enough to have the edge 20 19 located closely adjacent the glazing 14, and in lamps of such character, the described light-intercepting element gives excellent results when the rear edge of the cylindro-segmental portion 16 is in close 25 proximity to the upper portion of the reflecting surface of the reflector. In such case, the bulb is naturally placed well forward within the cylindro-segmental portion of the light-intercepting shield, as indicated by Fig. 30 9, as compared with Fig. 1.

The light-intercepting shield is interposed between the light source and the upper portion of the reflecting surface of the reflector. It follows that the upward rays which would 35 otherwise reach and be reflected by such upper portion, and cause an objectionable glare, are intercepted. By making the internal surface of the shield as a reflecting surface, these intercepted rays or at least 40 many of them, are reflected onto the lower portion of the reflecting surface of the parabolic reflector, and are thus utilized to form a part of the projected beam of light.

In the case of a lamp having an unusually 45 deep reflector, such as that shown in Fig. 1, the light source is necessarily located at a considerable distance from the glazing, and in this event it is found desirable to provide a disk-like, light-intercepting wall 20 nearer the light source. This wall may be, and 50 preferably is, segmental, and of the same general character as the wall 18, and is similarly provided with a horizontal edge 21, located below the axis AA. When this wall 55 is provided, its lower edge is substituted for the lower edge 19 of the wall 18, and instead of the plane BB, we have a plane CC containing the edge 21 and the lowermost portion of the filament 13.

60 The wall 20 may be, and preferably is, axially adjustable, and preferably also the cylindro-segmental wall of the shield is extensible, so as to adapt the shield to reflectors of different depths. One convenient 65 way of accomplishing this result is to make

the wall 20 as a part of a second and distinct light-intercepting element 22, having a cylindro-segmental wall 23 similar to the wall 16, and concentric therewith. One of these walls overlaps the other, so that in effect they constitute a single extensible wall. 70

As a means for securing the elements 15 and 22 in the desired position of adjustment, I have herein provided a clamping screw 24 and co-operating nut 25. The screw extends 75 through a perforation in the outer wall 16, and through a longitudinal slot 26 in the inner wall 23, while the nut 25 is preferably placed on the inside. The nut may be held against turning movement by a yoke 27, 80 provided with a pair of arms 28 extending through slots 29 in the wall 16, and through the slot 26 to the interior of the element 22, where said arms embrace the nut. The latter may be, and is herein provided with 85 notches 36 to receive the arms, and by this means the yoke and nut are securely interlocked against relative turning movement. Preferably the free ends of the arms are bent inwardly, as clearly shown in Fig. 6, 90 thereby to prevent the nut from dropping out of place in case the screw should be accidentally unscrewed too far. To adjust the element 22, it is necessary merely to turn the screw 24 to a sufficient extent to permit the member 22 to be moved lengthwise to the 95 desired position, whereupon it may be clamped in such position by again tightening the screw.

In the case of the light-intercepting element 22, the segmental wall 23 is for the most part disposed above the axis AA, although in the present example it is provided with two downwardly and forwardly inclined lateral portions 31. It should be 100 understood, however, that the lateral portions of both of the walls 16 and 23 may be variously shaped to suit the requirements of the particular lamp, but I have found in practice that this shape gives excellent results, because while providing for ample illumination of the foreground, it prevents the escape of glaring rays in a forward and lateral direction. This is a distinct advantage over some devices which prevent objectionable glare when viewed from directly 110 in front of the lamp, but permit the emission of glaring rays toward the side, so as to dazzle the eyes of a person who is just about to pass the vehicle on which the lamp is 115 mounted. 120

It should be understood that the invention is by no means limited to a shield having the described cylindro-segmental form, but that other shapes may be advantageously employed under certain circumstances. For example, I may, if desired, provide a shield 32, consisting of a segment of the frustum of a hollow cone, as represented in Figs. 7 and 8, in which case the internal reflecting 130

surface of the segmental wall is disposed at an advantageous angle to reflect the intercepted rays back onto the lower portion of the reflecting surface of the parabolic reflector, whence they are projected as a part of the beam.

In both forms, the shield is provided at the bottom and front with an opening to permit the passage of forwardly and downwardly directed, un-reflected rays as a diffused light onto the roadway, and to permit the passage of rays from the light source onto the lower portion of the reflecting surface, whence they will be concentrated and emitted through the front of the reflector as a beam. The effect of this is well illustrated in Figs. 3 and 4, more particularly Fig. 4, in which the concentrated rays forming the beam are shown in heavy, substantially parallel, horizontal lines, while the direct unreflected rays are shown as lighter, diverging lines intersecting the plane of the roadway at various points. It should be understood that in practice, the rays of the beam may be substantially parallel, as shown in heavy lines in Fig. 4, or somewhat divergent, forming a cone rather than a cylinder of light, depending of course on the location of the light-source with relation to the focal point of the reflector.

In either form of my invention, the light-intercepting element or elements may be supported by any suitable means, but in the present example, they are supported on the glazing 14, the latter to this end being provided with a perforation 33, to receive a bolt 34 which extends through the front wall of the shield, and is provided with a nut 35 by means of which the shield may be held in fixed position. I prefer to interpose between the glazing and the shield a washer 36, which may be formed of any suitable material, such for example as compression fiber, which is sufficiently yielding to insure a firm clamping action without danger of the glazing 14 being broken. If desired, the front wall 18 may be recessed or chambered as at 37, to bring the greatest pressure to bear at a considerable distance from the axis of the bolt and provide a somewhat yielding pressure due to the spring-like action of the central portion of the wall, as will be evident from an inspection of Fig. 6. Any suitable means may be provided for preventing the washer 36 from turning, but in the present example I have provided the wall 18 with a pair of forwardly extending lugs 38, engaging the lower edge of the washer, as best shown in Figs. 2 and 6. If desired, a second washer 39, also made of fiber, may be interposed between the head of the bolt 34 and the front face of the glazing 14.

Any suitable material may be used for the light-intercepting element or elements, and they may be either opaque or translucent.

When opaque, they are preferably made of metal, and preferably of aluminum, because of its lightness. When translucent, they may be made of celluloid, bakelite, or some similar substance, containing sufficient coloring matter to prevent the emission of glaring rays while still allowing the escape of more light than is the case with an opaque shield. In practice, however, I prefer to employ a metallic shield, because of its great strength and durability, and where aluminum is employed for this purpose, it possesses the additional advantage of excellent heat conductivity. This is a distinct advantage, as will be readily appreciated when it is considered that modern high power bulbs give out considerable heat, which is sometimes found to be injurious to the silvered surface of the reflector.

While I have herein shown and described two specific forms or embodiments of my invention for illustrative purposes, and have disclosed and discussed in detail the construction and arrangement incidental to two specific applications thereof, it is to be understood that the invention is limited neither to the mere details or relative arrangement of parts, nor to its specific embodiments herein shown, but that extensive deviations from the illustrated forms or embodiments of the invention may be made, without departing from the principles thereof.

Having thus described my invention, what I claim and desire by Letters Patent to secure is:

1. A lamp for vehicles comprising, in combination, a light-source, a light-concentrating reflector open at the front for the passage of both reflected and unreflected rays, light-intercepting means having a portion above the axis of said reflector and between said light-source and the upper portion of the reflecting surface of said reflector, and having another portion in front of said light-source and above and below said axis to obstruct the passage of forwardly emitted, unreflected rays above said axis and a part of those below said axis, said means having at its bottom and front an opening to permit the passage of forwardly and downwardly directed unreflected rays as a diffused light onto the roadway and to permit the passage of direct rays from said light-source onto the lower portion of said reflecting surface to be concentrated and emitted through the front of said reflector as a beam, a means to support said light intercepting means forward of light source and independently of said light source, said light intercepting means being separated from said light source and said reflector above the axis of the latter by a space permitting the upward escape of heat from said light source.

2. A lamp for vehicles comprising, in

combination, a light-source, a light-concentrating reflector open at the front for the passage of both reflected and unreflected rays, light-intercepting means having a portion above the axis of said reflector and between said light-source and the upper portion of the reflecting surface of said reflector, and having another portion in front of said light-source and above and below said axis to obstruct the passage of forwardly emitted, unreflected rays above said axis and a part of those below said axis, said means having at its bottom and front an opening to permit the passage of forwardly and downwardly directed unreflected rays as a diffused light onto the roadway and to permit the passage of direct rays from said light-source onto the lower portion of said reflecting surface to be concentrated and emitted through the front of said reflector as a beam, and means for supporting said light-intercepting means independently of said light-source, said light-intercepting means having its rear upper portion separated from said light-source and said reflector by a space permitting the upward escape of heat from said light-source.

3. A lamp for vehicles comprising, in combination, a light-source, a light-concentrating reflector open at the front for the passage of both reflected and unreflected rays, light-intercepting means having a portion above the axis of said reflector and between said light-source and the upper portion of the reflecting surface of said reflector, and having another portion in front of said light-source and above and below said axis to obstruct the passage of forwardly emitted, unreflected rays above said axis and a part of those below said axis, said means having at its bottom and front an opening to permit the passage of forwardly and downwardly directed unreflected rays as a diffused light onto the roadway and to permit the passage of direct rays from said light-source onto the lower portion of said reflecting surface to be concentrated and emitted through the front of said reflector as a beam, and a glazing at the front of said reflector, said light-intercepting means being supported by said glazing, said light-intercepting means having its rear upper portion separated from said light-source and said reflector by a space permitting the upward escape of heat from said light-source.

4. A lamp for vehicles comprising, in combination, a light-source, a light-concentrating reflector open at the front for the passage of both reflected and unreflected rays emanating from said light-source, light-intercepting means having a wall comprising a segment of a cylinder above the axis of said reflector and between said light-source and the upper portion of the reflecting surface of said reflector, and having a vertical

wall in front of said light-source above and below said axis to obstruct the passage of forwardly emitted, unreflected rays above said axis and a part of those below said axis, said means having at its bottom and front an opening to permit the passage of forwardly and downwardly directed unreflected rays as a diffused light onto the roadway and to permit the passage of direct rays from said light-source onto the lower portion of said reflecting surface to be concentrated and emitted through the front of said reflector as a beam, a means to support said vertical wall forward of said light-source providing for the support of said segment of the cylinder independently of said light source and separated therefrom and from said reflector by a space permitting the upward escape of heat from said light source.

5. Light-intercepting means for head-lights and search-lights comprising a plurality of axially adjustable shields, and means including a screw extending through said shields, a nut coöperating with said screw to secure said shields in the desired position of adjustment, and a yoke having a pair of arms engaging said nut to hold the same against turning movement.

6. Light-intercepting means for head-lights and search-lights comprising a plurality of axially adjustable shields, and means including a screw extending through said shields, a nut coöperating with said screw to secure said shields in the desired position of adjustment, and a yoke having a pair of arms extending through one of said shields and engaging said nut to hold the same against turning movement.

7. As a new article of manufacture, a light-intercepting shield for head-lights, comprising a disk-like segmental wall provided with an edge forming the chord of the segment, and a cylindro-segmental wall provided with two edges inclined with relation to the axis and joining the first-mentioned edge.

8. As a new article of manufacture, a light-intercepting shield for head-lights, comprising a disk-like segmental wall provided with an edge forming the chord of the segment, and cylindro-segmental wall provided with two edges which are in part substantially parallel with the axis and in part inclined with relation to said axis.

9. As a new article of manufacture, a light-intercepting shield for head-lights comprising a disk-like segmental wall provided with an edge forming the chord of the segment, and a cylindro-segmental wall provided with two edges which are in part substantially parallel with the axis and in part inclined with relation to said axis and join the first-mentioned edge.

10. A light-intercepting shield for head-lights and search-lights comprising an ex-

tensible cylindro-segmental wall and a disk-like segmental wall.

11. A light-intercepting shield for headlights and search-lights comprising an axially extensible cylindro-segmental wall and a disk-like segmental wall.

12. A light-intercepting shield for head-

lights and search-lights comprising an extensible cylindro-segmental wall and a disk-like axially adjustable segmental wall. In testimony whereof, I have signed my name to this specification.

ELLSWORTH A. HAWTHORNE.
